UNITED STATES PATENT OFFICE.

WALTER S. UPSHUR, OF NEWPORT NEWS, VIRGINIA.

MORTUARY VAULT FOR SHIPS.

No. 858,683.

Specification of Letters Patent.

Patented July 2, 1907.

Application filed November 20, 1906. Serial No. 344,331.

To all whom it may concern:

Be it known that I, WALTER S. UPSHUR, a citizen of the United States, residing at Newport News, in the county of Warwick and State of Virginia, have invented 5 certain new and useful Improvements in Mortuary Vaults for Ships, of which the following is a specification.

The object of my invention is to provide ships with vaults in which the bodies of those dying at sea may be 10 preserved until the ships reach port. Heretofore, so far as I am aware, no means has been provided for this purpose, the usual practice being to throw dead bodies overboard. So repulsive is this to many that they 15 refrain from taking an ocean voyage, and the thought of being thus consigned to the sea and made "food for fishes" is, to say the least, extremely unpleasant to others during a voyage.

In my companion application for patent No. 344,332 filed November 20, 1906, I have shown a coffin of suitable construction for receiving a dead body and storing it during a voyage. This coffin is so constructed and equipped that the body may be securely fastened and held against movement within the coffin which latter is provided with means for insuring a free circulation of 25 cold air around the body to prevent decomposition. According to my present invention I provide a vault of novel construction adapted to receive such coffins, hold them firmly against movement due to the motion of the ship, and securely store them against interference by unauthorized persons. The vault is provided 30 with means for refrigerating the air within it and is constructed to prevent the escape of cold air or the entrance of warm air, and also to avoid any increase of temperature within it by conduction from the outside through 35 its walls.

In the accompanying drawings I have illustrated the ways now best known to me of carrying out my invention, but the details of construction shown may be varied and some of the parts may be changed without 40 departing from the novel features of my improvements.

Figure 1 shows a vertical transverse section of the hull of a ship equipped with my improvements. Fig. 2 shows a longitudinal vertical section of one of my improved mortuary vaults, the section being taken 45 on the line 2-2 of Fig. 3 and looking in the direction of the arrow in Fig. 3. Fig. 3 shows a vertical transverse section of the vault on the line 3-3 of Fig. 2 looking in the direction of the arrow in Fig. 2. Fig. 4 is a perspective view of a part of the interior of the vault 50 showing certain details of construction therein and showing how one of my improved coffins is supported within the vault. Fig. 5 shows a front elevation of the vault and illustrates particularly the means employed for fastening the doors of the vault air-tight. Fig. 6 55 is a detail view in section showing the devices employed for bracing and tying together different parts

of the interior frame and the manner of supporting the rollers on which the coffins rest. Fig. 7 is a detail view in section illustrating particularly how the doors are hinged to the body of the vault and how the joint of 60 the doors with the vault body is rendered air-tight. Fig. 8 is a similar view showing another way of packing or rendering air-tight the joint of the doors with the body of the vault. Fig. 9 is a detail view in section showing the air-tight joint of the doors with each other. 65 Fig. 10 is a detail view in perspective showing the construction of the racks employed for supporting the refrigerating coils. Fig. 11 is a detail view in perspective of the clamping and locking devices for drawing the doors close against their air-tight packing. 70

The chamber, A, in which the vault, B, is located may be in any suitable part of the ship. The refrigerating plant, C, may be in its accustomed place and refrigerating pipes, D, are led from the plant to the vault, which is constructed in the manner presently described, being supported on channel beams or girders, 75 E, arranged on the deck beneath it and the vault may be suitably braced and held against vertical movement by braces, E', interposed between its top and the ceiling of the compartment in which the vault is located. 80

In front of the doors of the vault I arrange means for elevating, suspending and moving a coffin, X. This may be of any suitable construction. When the coffin arrives at the vault it may be supported on blocks, x in proximity to the vault, and the coffin may be elevated 85 by block and fall hoisting devices, X', of any suitable construction. These devices are preferably supported by overhead trolleys, X², arranged on rails, X³. The arrangement is such that the coffin may be easily elevated, then moved part way into the vault, and after 90 that the hoisting devices may be disconnected from the coffin and the latter pushed into the vault and locked therein in the manner hereinafter described.

I preferably employ in the construction of the vault 95 mild ship steel, commercial shapes being used where possible, brass wherever desirable, and where wood, cork and the like are used I employ the best obtainable material.

The outer shell, F, of the vault is preferably constructed of steel plate, such as boiler plate, connected 100 by angle irons, f, and the joints of the plates should be carefully calked. The vault is closed and the parts are made rigid at the bottom, top, two sides and back, while the front is provided with doors constructed and operated in the manner hereinafter described. The 105 shell is insulated in the following manner:—A wooden grating, G, of suitable construction is arranged on the inside of the shell, and to this grating are secured layers of cork, H, two layers being preferably employed, as illustrated. The inside of the cork layers is completely 110 covered with a zinc lining, I. While I have specified cork, zinc, etc., I do not wish to be limited to these

materials as equivalent materials may be substituted. There is an air-space, f' , between the shell, F , and the cork which affords additional insulation. I have not shown the details of joining the parts or of securing them together as these may be widely varied.

At the front of the vault I provide a door frame or casing, J . This is preferably constructed in the manner particularly shown in Figs. 2 and 8. This frame comprises beams, j , to which the zinc, cork and shell 10 are directly secured or connected. An angular recess is formed all around the beams in which is arranged bars, K , which are approximately Z-shape in cross-section, or they may be called double angle bars. One part, k , of the bar projects to the edge of the plate, F , 15 while the other part, k' , projects across the front face of the beam, j . Two doors, L , are preferably employed. They are hinged to opposite sides of the frame, J , and meet midway between the side frames, as indicated in Fig. 5. Each of these doors is hinged 20 at, M , to the sides of the frame, J , in the manner illustrated in Figs. 5 and 8. It will be observed that the hinges extend across the recesses in the frame and permit the doors to be thrown wide open, and to be properly closed. The doors are preferably constructed 25 in the manner shown in Fig. 2. The outer frame, l , has secured to its outer face a shell or plates, l' , similar to the plates, F , and just within the shell is arranged a wooden grating, l'' , similar to the grating, G . Upon the grating is applied layers of cork, l'' , and 30 sheet zinc, or similar material, l''' , is applied inside the layers of cork. While the materials specified are preferred, other materials may be employed, and different arrangements may be adopted for obtaining strength combined with proper insulation.

35. I arrange a thermometer, N , in one of the doors in a suitable frame, N' , which is provided with a window; N^2 . By this means the temperature within the vault may be readily determined.

I deem it important that the joints of the doors with 40 each other and with the door frame should be air-tight. The doors overlap and connect with each other in the manner particularly shown in Fig. 9. The frame of one of the doors is formed with a recess, o , in which is arranged vertically a wire or rod, O , 45 over which is stretched rubber or similar soft material, o' , held in place by strips, o'' . The other door has an overlapping portion, O' , adapted to come in contact with the rubber, o'' . When the doors close together and are clamped in place, the rubber is 50 pressed and by this means an air-tight connection is afforded. The joints of the doors with the door frame, J , are also packed, preferably in the manner indicated in Fig. 8. The front plate or shell, l' , of each door is provided with a projecting portion, l'' , flanged at l''' . 55 The frame, J , is provided all around its edge with wires or rods, P , over which is stretched rubber or similar soft material, p , held in place by metal strips, p' . The flanges, l'' , come in contact with the rubber when the doors are closed and when the doors are locked 60 and clamped the rubber is compressed and affords air-tight joints.

In order to insure the compression of the packing material, I provide clamping and locking devices, Q , shown in detail in Fig. 11, each consisting of a hasp, q , 65 a pad eye, q' , a threaded eye-bolt, q'' , and a clamping

nut, q''' . The hasps or slotted plates, q , are attached to the doors at their outer edges at the points indicated in Fig. 5, there being one located at the side edge of each door midway between its hinges, M , one at the top of each door near its edge which meets the 70 other door, and another at the bottom of the door near its meeting edge. The pad-eyes are attached to the Z-bars, K , in the manner clearly shown in Figs. 5 and 8. The eye-bolts, q'' , are joined to the pad-eyes in the usual way and are free to swing in any direction when loose. When the nuts, q''' , are loosened the bolts may be swung out of engagement with the hasps, q , and the doors may be swung open. When the doors are shut, the bolts may be made to engage the hasps and then if the nuts, q''' , be tightened the doors will be 80 drawn close against the rubber packing and insure an air-tight joint all around. Any suitable locking device, R , may be employed. I have shown a conventional device for this purpose, but other locks may, of course, be substituted.

85 In Fig. 7 I have shown a slightly modified construction. In this figure of the drawings, a strip of packing material, r , is applied to a projecting portion, r' , of the door, and this packing material is made to engage the adjacent edge of the Z-bar, K .

Within the vault is arranged a frame for supporting the refrigerating coils, S , and the coffins, X . This frame is preferably constructed in the following way:— Plates, T , of sheet steel, such as boiler plate, and having 95 ventilating openings, t , which are also for the purpose of lightening the material, are connected by angle irons, t' , or in any other suitable way to the shell, F . Two of these plates are arranged a short distance apart in the central portion of the vault and extend from top to bottom thereof backwardly to within a short distance from the back of the vault, and forwardly to within a short distance from the doors. Two similar plates, T , are arranged in a similar way a short distance 100 from the opposite side walls of the vault. Air can freely circulate around the front and rear ends of the plates 105 and also through the openings, t .

Vertically arranged rack bars, U , preferably made of angle iron, as shown in Fig. 10, are secured to the outside of the outside plates, T , and support the refrigerating coils in the manner shown. These angle irons 110 also serve to stiffen the outer plates, T , while the inner plates are stiffened by means of stiffening strips, t'' , arranged vertically and lying against the adjacent surfaces of both of the inner vertical plates. In order to further stiffen the frame and to provide supports for 115 the anti-friction rollers, V , I employ horizontally arranged rods, W , which extend straight through all four of the vertical plates, in the manner clearly shown, as well as through the racks, U , and the stiffening strips, t'' . These bars are secured in place in the manner presently described.

120 Rollers, V , are arranged on the rods, W , to receive the coffins, X , which are provided with metal strips, z , to bear against the rollers. Each of the rods, W , is threaded at opposite ends, as indicated at w , and also 125 centrally or midway between its ends at w' , see Fig. 6. The outer roller, V , on each rod, W , is held between a washer and collar, V' , and a washer and nut, V'' . The collar, V' , may be fastened in place by a set screw while the nut, V'' , is applied to the threaded end, w , 130

inside the outer plate, T. A nut, V³, is applied to the threaded end of the rod which projects outwardly from the rack bar. In this way the rod is firmly secured to the outer vertical plate, T, while the roller 5 is held in position but is free to rotate on the rod. The opposite end of the rod is applied to the opposite outer plate, T, in a similar way and the outer roller next the other outer plate is also mounted in a similar manner. The rods, W, extend through the inner vertical plates, 10 T, and the stiffening strips, t². The rollers, V, next the central plates, T, are each mounted between a collar, V⁴, and a washer, v³, on one side and a washer v⁴ and a nut, V⁵, on the opposite side and are free to rotate on the rod. The nut, V⁵, and a nut, V⁶, serve 15 to clamp the rod, W, to the central plates, T. The rods, W, are arranged in such vertical and horizontal planes as to hold the rollers, V, in proper position to receive and support the coffins.

I have shown the vault adapted to receive six coffins, 20 but, of course, it may be constructed to receive a greater or less number and some parts of the frame will, of course, be differently proportioned when the vault is adapted to receive a different number of coffins. In order to prevent the coffins from being pushed so 25 far back into the vault as to strike the insulation, or the zinc coating thereof, I provide a stop plate, Y. This is secured in any suitable way, as by angle irons, y, to the central plates, T, and need only be large enough to come in contact with a portion of the rear 30 ends of the coffins, as illustrated in Figs. 2, 3 and 4. When the coffins are inserted they are pushed back against the stop plate, Y, and are held against the plate by means of cross bars, Y', which engage catches, Y², secured to the vertical plates, T. By these means 35 the coffins are securely held in place and are unaffected by the rolling of the ship.

The details of construction of the coffin, X, are fully shown, described and claimed in my application for 40 patent No. 344,332, above referred to. It may be said, however, that the box or outer casing, Z, is perforated so as to permit the entrance of cold air. Within the box is an enameled inner receptacle, Z', provided with a perforated false bottom, Z², which is held above the bottom of the vessel, Z', by cleats, Z³, and is centered 45 or held away from the walls of the vessel, Z', by laterally projecting arms, Z⁴. The cover, Z⁵, of the coffin is held in place by securing devices, Z⁶, and the false bottom, Z², is held down by means of vertical posts, Z⁷, which engage the perforations in the false bottom 50 and in the cover. A head piece, Z⁸, and a foot piece, Z⁹, are adjustably secured in the coffin so that they may be made to bear against the head and feet of the corpse to hold it against endwise movement, and adjustable cross bars, Z¹⁰ are employed for holding the body down 55 upon the false bottom. In this way any injurious movement of the body within the coffin is prevented.

By my improvements the body of one dying at sea may be secured in a coffin or casket in such manner as to be held against movement therein in any direction and yet may be free from danger of decomposition because of a free circulation of cold air all around it. The refrigerating coils may be of such capacity as to keep the interior of the vault at the proper temperature and inasmuch as the vault is thoroughly insulated 65 there need be no waste of the refrigerating means or

any undue burden imposed on the refrigerating plant. The vault is of fire proof and burglar proof construction and the doors can, of course, be securely locked against the entrance of unauthorized persons. It is, therefore, by reason of my improvements entirely feasible to 70 preserve a dead body aboard ship instead of throwing it overboard, as has heretofore been the custom. A body may be preserved in this way during a long voyage, and when the ship arrives at port the body, in a perfect state of preservation, may be transferred 75 to a suitable coffin or casket and consigned to a proper destination for interment in the ordinary way.

I claim as my invention:

1. A mortuary vault for ships comprising a body portion made fire and burglar proof and lined with insulating material, a coffin supporting frame within the vault, a stop arranged at the rear end of the frame for preventing the coffins from moving rearwardly and means at the front end of the frame for holding the coffins against the stop and for preventing forward movement thereof. 80

2. A mortuary vault for ships comprising the outer shell or casing, the grating applied thereto provided with air spaces, layers of insulating material applied to the grating, a metallic lining for the insulating material, a coffin supporting frame within the vault and means for holding the coffins against endwise movement thereof. 90

3. A mortuary vault for ships composed of an outer casing and an inner frame comprising the ventilated vertical plates, horizontally arranged rods joining the plates and tying them together and rack-bars for stiffening the plates and supporting the rods. 95

4. A mortuary vault for ships comprising a body portion and an inner frame consisting of vertically arranged plates, horizontally arranged rods tying the plates together and bracing them and rollers mounted on the rods for supporting the coffins. 100

5. A mortuary vault for ships comprising a body portion, vertically arranged plates therein, rack-bars secured to the plates and refrigerating coils mounted in the rack-bar. 105

6. A mortuary vault for ships comprising a body portion, a door rendered air-tight, inner frame plates securely fastened to the body portion of the vault, means for stiffening the frame, horizontally arranged rods for tying the plates together and bracing them, rollers carried by the rods, a stop plate secured to the rear end of the plates and locking bars applied to the plates at their front ends. 110

7. The combination of an air-tight vault, a coffin supporting frame within the vault constructed to provide for a free circulation of cold air, means for holding the coffins steady in their frame, refrigerating means within the vault, and a perforated coffin constructed to provide for a free circulation of cold air within it. 115

8. The combination of a burglar and fire proof vault lined with insulating material and provided with an air-tight door, a coffin supporting frame within the vault constructed to provide free circulation of cold air, means for holding the coffins steady in their frame and a perforated coffin constructed to provide for a free circulation of cold air and provided with means for securing a corpse against movement within it. 120

9. The combination of a mortuary vault constructed of heat insulating material and provided with an air-tight door, a coffin supporting frame within the vault constructed to provide free circulation of cold air, means for circulating a refrigerating medium in the vault, means for holding the coffins steady in their frame and a coffin having openings to permit cold air to come in contact with the corpse and provided with means for securing the corpse against movement within it. 125

In testimony whereof, I have hereunto subscribed my name. 130
